(57) **CLAIM**

The ornamental design for a hose reel, as shown and described.

DESCRIPTION

FIG. 1 is a front perspective view of a hose reel showing our design.

FIG. 2 is rear perspective thereof.

FIG. 3 is a front elevation view thereof.

FIG. 4 a left side elevation view thereof.

FIG. 5 is a right side elevation view thereof.

FIG. 6 is a top plan view thereof.

FIG. 7 is a bottom plan view thereof; and,

FIG. 8 is a sectional view thereof along line 8-8 shown in FIG. 3.

The broken lines in drawings depict portions of the hose reel and form no part of the claimed design.
